United States Patent Office

Des. 227,271

Patented June 12, 1973

227,271

ANIMAL IDENTIFICATION TAG

Harley E. Nichols, Jr., Hardwick, Vt., assignor to
C. H. Dana Company, Inc.

Filed Mar. 4, 1971, Ser. No. 121,239

Term of patent 14 years

Int. Cl. D30—08

U.S. Cl. D30—43

FIG. 2

FIG. 1

FIG. 3

FIG. 4

FIG. 5

FIG. 1 is a front elevational view of an animal identification tag, showing one form of my new design;

FIG. 2 is a left side elevational view of the form shown in FIG. 1;

FIG. 3 is a right side elevational view of the form shown in FIG. 1;

FIG. 4 is a front elevational view of an animal identification tag, showing a second form of my new design; and

FIG. 5 is a front elevational view of an animal identification tag, showing a third form of my new design.

I claim:

The ornamental design for an animal identification tag, as shown and described.
